UNITED STATES PATENT OFFICE.

WILLIAM PORTERFIELD CUTLER, OF BALTIMORE, MARYLAND.

SAIL.

SPECIFICATION forming part of Letters Patent No. 397,589, dated February 12, 1889.

Application filed September 6, 1888. Serial No. 284,702. (No model.)

To all whom it may concern:

Be it known that I, WILLIAM PORTERFIELD CUTLER, a citizen of the United States, residing at Baltimore, in the State of Maryland, 5 have invented certain new and useful Improvements in Sails, of which the following is a specification.

My invention relates to sails, particularly to the jib-sails of sailing-vessels. Heretofore, 10 usually, the head and foot bias parts of this class of sails have been united at their ends by a lap-seam, at the outer end of which seam the clew was secured, and the sail was formed of strips of canvas which extended in parallel widths diagonally across the sail from the foot or bottom to the head or top of the same. The bias sections of canvas forming the head and foot portions of such sails were so cut 15 that the breadths or strips forming them extended in a parallel direction with the leech and foot ropes. Subsequently jib-sails were formed by making the sail in a single section or piece on a bias, so that the ribs or lengths of canvas composing the sail were short and 20 extended diagonally across the sail along its entire length from head or stay rope to leech and from the head or stay rope to the foot-rope. In addition to thus making the sail on a bias, a re-enforcing bias-cut piece or gusset 25 was secured transversely across the widest or middle portion of the sail, extending on each side from the clew to the "head" or "stay" rope. Parting of the sail along the seams extending transversely of the sail to the clew 30 often occurs, in which case the sail is rendered useless. Injury to the jib-sails of a vessel usually occurs at a time when the vessel is under full headway, and frequently during a gale, when repairs of this nature cannot be 35 judiciously attempted.

The object of my invention is to so form the sails that the defects above mentioned will be obviated, as will be hereinafter more fully described.

40 In the drawings, Figure 1 is a view of a jib-sail constructed in accordance with my improvements, and Fig. 2 is a view of the gusset or strengthening-strip.

In carrying out my invention I form the

sails—which I term "reversible diagonal-cut 50 jib-sails," although the improvement may be applied to other forms of sails—of two parts, A and B, which parts A B are formed of widths or strips, C and D, of cloth, the seams of which run in reverse or diverging directions from the middle line of the bolt-rope H and completed sail to the leech-rope E and foot-rope F.

The portions A B of the sail are united at their wider ends by a double seam, and in addition to this double seam a gusset or strengthening-piece, I, is employed and extends on both sides of the sail from the clew to the middle of the head or stay rope, the clew being secured to the sail after the gusset I has 65 been stitched to place in the usual manner.

In the prior constructions of this class of sails, where the longest cloths and seams were employed at and near the widest part of the sail, I use comparatively the shortest cloths 70 or strips, and consequently shorter seams. Further, by my construction I greatly reduce the bias upon the stay or head rope, the wider ends of the portions receiving a considerable portion of the bias, thereby rendering the sail 75 less liable to stretch out of proportion in hoisting the sail or during the pitching of the ship. Besides these advantages, my construction presents more bias on the leech and foot, where the sail must give more or less in order to make a perfect-setting sail.

Having thus fully described my invention, what I claim, and desire to secure by Letters Patent, is—

A reversible diagonal-cut two-part sail 85 formed of widths or strips of cloth, C and D, the seams of which run in reverse or diverging directions from the middle line of the bolt-rope H or completed sail to the leech-rope E and foot-rope F of the sail, the diverging seams 90 in the respective portions of the sail being parallel, as set forth.

In testimony whereof I affix my signature in presence of two witnesses.

WILLIAM PORTERFIELD CUTLER.
